UNITED STATES PATENT OFFICE.

HENRY KRAUT, OF SUMMIT, NEW JERSEY.

TOOL.

1,196,703.

Specification of Letters Patent. Patented Aug. 29, 1916.

Application filed September 17, 1912. Serial No. 720,856.

To all whom it may concern:

Be it known that I, HENRY KRAUT, a subject of the Emperor of Germany, residing at Summit, in the county of Union and State 5 of New Jersey, have invented new and useful Improvements in Tools, of which the following is a specification.

This invention relates to certain new and useful improvements in tools and more especially to a combination tool that may be 10 used for various purposes.

To these ends the invention consists in the novel details of construction and combination of parts more fully hereinafter described and particularly pointed out in the 15 claim.

Referring to the accompanying drawings forming a part of this specification in which like numerals designate like parts in all the 20 views:—Figure 1 is a side elevational view of my improved tool. Fig. 2 is a cross sectional view taken on the line 2—2 of Fig. 1, and Fig. 3 is a cross sectional view taken on the line 3—3 of Fig. 1.

The tool is provided with the handle 1 through which is passed and securely held 25 therein two parallel wire rods 2 and 3. These rods extend approximately an equal distance beyond the ends of the handle and have securely held to their outer ends stationary jaws 4 and 5, the upper part of the 30 jaw 4 of which forms the stationary jaw 6 of a monkey wrench, and the lower part of which is extended to form a hammer 7.

Slidably mounted on the rods 2 and 3 is the movable jaw 8 of the wrench which is provided with a recess 9 within which is mounted an adjusting screw 10. The adjusting screw contacts with the screw threaded 35 portion 11 on the rod 2 and is adapted to hold the sliding jaw 7 of the wrench in any desired adjusted position.

A scale or rule 12 is provided on the lower side edge of the handle 1 which may be conveniently used for quick measurement when desired.

The stationary jaw 5 secured to the outer ends of the rods 2 and 3 opposite to the wrench end, forms the stationary jaw of a 50 clamp and is provided with an upwardly extending clamp portion 13 and a lower extending clamp portion 14, which portion 14 is also provided with a semi-cylindrical groove or recess 15, which is adapted to re-

ceive and to hold a small piece of soldering 55 wire when the clamp is used as a soldering device. A sliding jaw 16 provided with the upper and lower extending clamp portions 17 and 18, is slidably mounted on the rods 2 and 3 and is normally held in contact with the stationary jaw 5 by means of a spring 19 surrounding the rod 3 and bearing at one end against the movable jaw 16 and at its other end against the handle 1.

When the clamp is desired to be used, for 60 instance if it is desired to be used as a soldering device, the movable jaw is first opened against the tension of the spring, a small piece of soldering wire is then inserted 65 between the smooth vertical gripping faces upon the jaw or disposed within the groove and the movable jaw is released to engage 70 with the soldering wire at a point diametrically opposite the center thereby securely clamping the soldering wire and holding the 75 same in a rigid manner.

From the foregoing it will be seen that by the use of a tool constructed in accordance 80 with my invention, not only a great saving of time will be effected but that a comparatively simple, cheap and durable tool will always be ready for use and that the parts cannot become separated and misplaced or lost.

It is obvious that those skilled in the art 85 may vary the details of construction and arrangements of parts without departing from the spirit of my invention and therefore I do not wish to be limited to such features except as may be required by the claim.

What is claimed as new is:

In a wrench, in combination, a bar-like handle, a pair of parallel wire rods extending forwardly of said handle and secured thereto at one end, a stationary jaw secured centrally upon both of said wire rods and having a flat side projecting in opposite directions and at right angles from said rods to provide an upper and lower extending clamp portion, one of said clamp portions longitudinally and terminally recessed to form a groove opening out of its flat side and through its end as well, a sliding jaw having openings through which both of said rods project and also having a flat side 100 adapted to contact the flat side of said stationary jaw and also providing upper and lower clamp portions one of which is adapt-

ed to close the side of said recess in the stationary jaw so as to leave its end open only, and a spring coiled around one of said rods bearing against said bar-like handle at one end and against said slideable jaw at its opposite end to hold the two jaws closed.

In testimony whereof I affix my signature in presence of two witnesses.

HENRY KRAUT.
